UNITED STATES PATENT OFFICE.

MIRON G. TOUSLEY, OF ENGLEWOOD, ILLINOIS, ASSIGNOR TO ARMENA PATRICK, OF SAME PLACE.

TABLE-WAITER.

SPECIFICATION forming part of Letters Patent No. 415,131, dated November 12, 1889.

Application filed April 9, 1889. Serial No. 306,576. (No model.)

To all whom it may concern:

Be it known that I, MIRON G. TOUSLEY, a citizen of the United States, residing at Englewood, in the county of Cook and State of Illinois, have invented certain new and useful Improvements in Table-Waiters; and I do hereby declare that the following is a full, clear, and exact description of the same, reference being had to the annexed drawings, making a part of this specification, and to the letters and figures of reference marked thereon.

This invention relates to certain new and useful improvements in revolving table-waiters of that class designed to stand on a table where a group of lighter supply-dishes are ordinarily placed, so that any one at the table can revolve the same to bring the desired article within his or her reach.

The objects of the invention are to provide a portable device for use on any ordinary dining-table, which shall combine in the one article lightness, durability, ease in operation, and attractiveness.

To the accomplishment of the above ends and to such others as the invention may pertain, the same consists in the peculiar combinations and the novel construction, arrangement, and adaptation of parts, all as more fully hereinafter described, shown in the drawings, and then particularly pointed out in the appended claims.

The invention is clearly illustrated in the accompanying drawings, which, with the letters of reference marked thereon, form a part of this specification, and in which—

Figure 1 is a top plan of my improved waiter. Fig. 2 is a central vertical transverse section of the same. Fig. 3 is an enlarged sectional detail of the parts at the pivot.

Referring now to the details of the drawings by letter, A designates the top, which may be of any desired shape and size, and is formed at its outer edge with a downwardly-extending slightly outwardly-inclined rim a, preferably scalloped, as shown. This rim adds to the appearance of the device and serves as a means for turning the said top by placing a finger underneath in a manner which will be readily understood, which pre-

vents soiling of the polished surface of the top. This top is made as fanciful as may be desired, and is made of metal, so as to give strength and durability and to provide for plating, enameling, or japanning, as may be desired. This top is open-work or perforated to give lightness to the same, as well as to add to the ornamental appearance of the same. This top is provided centrally with a hole b, slightly countersunk, as shown, and at equidistances from said hole the under side of the top is formed or provided with the downwardly-extending lugs or points, which are adapted to ride in a groove or track in the base portion, soon to be described.

C is the base, which is small in comparison with the top, as shown, and has its sides inclined outwardly and downwardly to give it a firm bearing, and the bottom edge may be made plain, as shown, or with pedals, if desired. This base is formed around its top edge with a circular groove or track, the shape of which may be varied somewhat, and in this track or groove work the downwardly-extending lugs c on the top, as shown best in Fig. 2. The base at its center is formed with a vertical boss e in the center of the circle formed by the track or groove d, and extending slightly above the top edge thereof, and on its under side provided with a squared socket, or hole f, to receive the nut which holds the parts together.

In practice the top is laid upon the base portion, with the lugs c in the groove or track d, and the hole b in the top coincident with the hole in the central boss of the base. A screw D is then passed through the hole in the top and the hole in the boss, and a nut g screwed thereon. Said nut, being confined in the squared socket in the under side of the boss, is prevented from turning. A tube h is fitted to the hole in the top and the hole in the boss, and may be fixedly attached to either the top or base or to the screw, this being immaterial; but the use of the tube is considered of special importance, as it forms a means of receiving the friction of the parts, permits of setting the screw or bolt and nut tightly beyond the power of tightening or unscrewing by the revolving of the top and without binding the attached parts. The head of

the screw or bolt is seated in the counter-sink in the top, as shown, although this counter-sink might be omitted without materially affecting the other features of construction, 5 but is preferred, as it gives a more finished appearance.

The device sits at any desired place on the table, and one or more may be employed, as the length of the table may require.

10 The base may be of such a height that plates may be set upon the table beneath the top without being interfered with in the revolution thereof.

15 The whole device is enameled, plated, or otherwise treated to give it as ornamental an appearance as the wishes of the purchaser or manufacturer may dictate.

20 The parts being all of metal avoid the danger of warpage, shrinkage, and twisting out of order in the revolution of the top, and enable me to provide the parts separately and warrant their fitting.

25 The track or groove in which the lugs of the top work should have a suitable lubricant placed therein to decrease the friction between the parts; but this may be omitted.

30 The parts may be readily detached for packing and as readily put together by any person without the employment of skilled labor.

The sides of the groove or track in the base are preferably inclined and the bottom substantially flat, and the sides of the lugs on the top are also preferably slightly inclined,

so as to allow a little freedom of the parts 35 and allow the top to tip slightly without binding of the parts.

What I claim as new is—

1. In a portable revolving table-waiter, the combination, with the top formed with central hole, and the base having central boss having a hole therein, of the screw passed through said holes and provided at its lower end with a nut, and the tube loosely embracing said screw and fitted in said holes, serving as a bearing between the base and tabletop and preventing contact of the table-top with the screw, substantially as and for the purpose specified. 40

2. The combination, with the perforated metallic top having a central hole, and the base formed with a central boss having a hole therethrough, and a squared socket upon its under side, of the screw passed through said holes, the tube around said screw in said 45 holes serving as a bearing between the base and tabletop and preventing contact of the table-top with the screw, and the nut upon the lower end of the screw within said socket, substantially as shown and described. 50

In testimony that I claim the above I have hereunto subscribed my name in the presence of two witnesses.

MIRON G. TOUSLEY.
